UNITED STATES PATENT OFFICE.

WILLIAM H. PHILLIPS AND ORA G. WILLIAMS, OF SACRAMENTO, CALIFORNIA.

FLY-EXIT FOR WINDOW AND DOOR SCREENS.

No. 853,419.

Specification of Letters Patent.

Patented May 14, 1907.

Application filed July 27, 1906. Serial No. 328,113.

To all whom it may concern:

Be it known that we, WILLIAM H. PHILLIPS and ORA G. WILLIAMS, citizens of the United States, residing at Sacramento, in the county 5 of Sacramento and State of California, have invented certain new and useful Improvements in Fly-Exits for Window and Door Screens, of which the following is a specification.

10 Our invention relates to devices in the nature of fly exits for window and door screens and has for its object the provision of a device which can be readily attached to screen frames in common use, the device consisting 15 of a number of separate overlapping units capable of attachment to the top of the window or door screen frame of ordinary construction.

10 The construction and advantages of my invention will be described in detail hereinafter and illustrated in the accompanying drawings in which—

20 Figure 1 is a view of the upper fragment of a door or window screen frame showing my improved exit in position, Fig. 2, a cross sectional view, and Fig. 3, a detail view of the exit sections.

25 In the drawings similar reference characters indicate corresponding parts throughout the several views.

30 A represents the frame of a screen door or window having the screen fabric B cut away at the upper end leaving an opening C at the top of the frame. The exit D consists of one 35 or more plates of sheet metal E secured in opening C. Each of said plates E has its middle portion curved inwardly as shown at F. The upper edges of plates E are formed with a flat portion G and have angular ears H 40 integral therewith and secured to frame A. The lower edge of each plate E is also formed flat as shown at I against which the top of screen fabric B rests. J indicates ears formed by extending the outer edge of the outer section plates E opposite the flat portions I 45 which are secured to the side rails of frame A.

50 The edges of plates E are bent back on themselves as shown at K, one of the end plates having the bent back portion for its whole length while the other plates have the 55 bent back portion at one end cut away so that the single thickness of metal may slip in between the bent back portion and the body of the plate on the adjoining section.

55 It will be understood from this construction that the exit D may be adjusted to fit

any length of opening C by taking the number of plates necessary to approximately fill the space and then adjusting them by sliding them on one another so as to completely fill 60 the space. If desired a strip of screen fabric or other material L may be secured on the inner side of the frame A over exit D so as to form a chamber M but this is not essential to a successful operation of our invention as it 65 will be understood that the insect in crawling up the screen will be attracted by the light coming through the opening between flat portion G and the frame A and will crawl therethrough and out of the room.

70 Having thus described our invention what we claim is—

1. In combination with a frame, and a screen fabric secured thereto with an opening between its top edge and the top rail of the 75 frame, a plurality of plates secured in said opening having their edges bent back on themselves to form slideways, a part of said bent back portion on the plates cut away to fit the slideway on an adjacent plate, the central longitudinal portion of the plates bent inwardly leaving the upper and lower edges flat, angular ears projecting from the upper edge of the plates to space them away from the top rail of the frame, and ears projecting 80 from the lower edges of the end plates to secure them to the side rails of the frame, substantially as shown and described.

2. In combination with a frame, and a screen fabric secured thereto with an opening 90 between its top edge and the top rail of the frame, a plurality of plates secured in said opening having their edges bent on themselves to form slideways, a part of said bent back portion on the plates cut away to fit the 95 slideway on an adjacent plate, the central longitudinal portion of the plates bent inwardly leaving the upper and lower edges flat, angular ears projecting from the upper edge of the plates to space them away from the 100 top rail of the frame, ears projecting from the lower edges of the end plates to secure them to the side rails of the frame, and a strip of fabric secured over said plates and forming a chamber therewith, substantially as shown 105 and described.

3. In combination with a frame, and a screen fabric secured thereto with an opening between its top edge and the top rail of the frame, a plurality of plates secured in said 110 opening having their central longitudinal portions bent inwardly leaving their upper

and lower edges flat, one of said plates having its flat surfaces bent back on themselves for its entire length to form slideways, the others of said plates having a portion of the upper and lower flat surfaces bent back on themselves to form slideways and the other part cut away to fit in the slideways in the adjacent plate, angular ears extending from the upper edges of the plates to space them ⁵ away from the top rail of the frame, and ears

extending from the lower edges of the end plates to secure them to the side rails of the frame, substantially as shown and described.

In testimony whereof we hereto affix our signatures in the presence of two witnesses: ¹⁵

WILLIAM H. PHILLIPS.

ORA G. WILLIAMS.
